UNITED STATES PATENT OFFICE.

EDWIN CROMPTON AND CHARLES L. CROOKS, OF PUEBLO, COLORADO.

LOCK OR LATCH.

Application filed August 26, 1919. Serial No. 319,970.

To all whom it may concern:

Be it known that we, EDWIN CROMPTON and CHARLES L. CROOKS, citizens of the United States, residing at Pueblo, in the county of Pueblo and State of Colorado, have invented certain new and useful Improvements in Locks or Latches; and we do hereby declare the following to be a full, clear, and exact description of the invention, such as will enable others skilled in the art to which it appertains to make and use the same.

This invention relates to locks or latches and more particularly to locks or latches adapted for use on automobile and similar doors, but it will be obvious that certain features of the invention may be employed in locks or latches of other types.

It is important that such locks and latches be reliable in operation and readily assembled. It is also desirable that the lock shall be automatically operable by a keeper or strike plate as the door is closed, and that it shall be manually operable by the same hand that opens the door. It is also important that the door shall be securely locked or latched when it is closed, so that it will not open accidentally.

One of the objects of this invention is to provide a lock that has few and simple parts so that it may be readily assembled and will not easily get out of order. Another object is to provide a lock or latch mechanism having a novel operating means which is so arranged that the locking or latching element is positively and automatically moved from engagement with the keeper or strike plate as the door is closed, and may be manually disengaged from the keeper by the hand that opens the door. Still another object is to provide a lock that securely locks the door when the latter is closed.

According to the present invention the lock or latch mechanism comprises cam operating means that cooperates with the locking or latching element to cause its withdrawal into the casing. Such positive operating means for the locking or latching element permits the use of a relatively long locking element or bolt and deep socket in the keeper to receive such element. In addition, the lock or latch is also provided with means for retaining the bolt in a locked or latched position, such retaining means being

releasable by the operating means before the cam means begins to move the bolt away from the keeper.

The above and other objects and the novel features of this invention will be apparent from the following description taken in connection with the drawings, which illustrate one particularly desirable form in which the principles of the invention may be embodied. In these drawings,

Figure 1 is a vertical sectional view of the lock as it appears in locked or latched position, certain parts of the mechanism being shown in elevation;

Figure 2 is a similar view, with the parts shown in unlocked or unlatched position;

Figure 3 is a transverse sectional view on the line 3-3 of Figure 1; and

Figure 4 is a perspective view of the keeper or strike plate that cooperates with the lock or latch mechanism.

Referring to the drawings, 10 designates a U-shaped metal casing which is open at the rear and at its upper and lower ends and is adapted to support the lock or latch mechanism within a mortise in the automobile door, preferably in such a position that the front wall 101 of the casing is flush with the edge of the door and also so that the upper end of the operating member or plunger P shall project adjacent to the upper edge of the door where it may be engaged by the hand that opens or closes the door. The plunger P is provided with suitable means, such as a button 11 at its upper end for operating the same.

The front 101 of the casing 10 has two openings 12 and 13 therein, one vertically above the other, such openings being arranged to register respectively with a recess 14 and a socket 15 in a keeper or strike plate K that is secured in the recess of the door jamb and flush with the edge of such door jamb, in the usual manner.

The socket 15 is adapted and arranged to receive the locking element or bolt L of the lock or latch, which may be of any suitable form but as illustrated has a head or knob consisting of an elongated cylindrical body part having a rounded or hemispherical outer end adapted to fit snugly in a corresponding hemispherical socket 15. The bolt L is comparatively long and the socket 15 is comparatively deep to receive it so that

the parts will lock or latch the door more securely than the shorter knobs or bolts and shallower sockets heretofore known.

The bolt L normally projects through the opening 13 in the casing and is supported in such projected position by a leaf spring 16 that carries the bolt L at its upper free end and is secured at its lower end to the inner side of the front wall 101 by the rivets 17 or other securing means.

The bolt may be operated from the plunger or operating member P by any suitable cam means that will move the bolt far enough into the casing 10 to allow the keeper plate to pass it when the door is swung open and closed. The arrangement herein illustrated is a particularly simple and reliable construction in which the cam member is carried by the plunger and engages a part 20 of the bolt to produce a camming action that will cause the bolt to be retracted into the lock casing. In the particular arrangement illustrated a U-shaped stem 18 is secured to the inner end of the bolt L and between its 25 limbs rotatably supports an anti-friction roller 19 that is normally in contact with and engageable by the downwardly inclined cam surface 20 on the lower edge of a cam arm 21 rigidly mounted on the vertically reciprocable plunger P. The rear ends of the stem 18 extend upwardly on opposite sides of the cam arm 21, as at 22, to serve as guiding means and keep the arm 21 in proper alignment with the roller 19.

The plunger or operating member P is vertically reciprocable in guide openings in two guide and bracing plates 23 and 24 which bridge the space between the side walls of the casing and are secured thereto. Suitable means may be provided for retaining the bolt L in its locking or latching position in the socket 15, such means being preferably released automatically when the door is to be opened. A simple and desirable arrangement is herein illustrated and consists of a retaining or locking plate or dog 25 which is provided at its rear end with oppositely disposed projections or lugs 26 that fit in openings in the side walls of the lock casing to pivot the retaining plate 25 adjacent its rear end, the forward end 27 of the retaining plate being free to swing up into position against the leaf spring 16 and behind the bolt L to retain the latter in locked position.

Suitable means are provided for automatically releasing the locking plate or dog 25. In the desirable arrangement here illustrated, the plate is provided with an elongated aperture 28 through which the plunger P is adapted to extend, and upon the plunger P there are laterally extending pins 29 adapted to engage the upper side of the plate and swing the end 27 thereof downwardly out of retaining or dogging position,

when the plunger P is depressed. A helical spring 30 that surrounds the plunger P and bears at its lower end upon the guide or brace 24 and at its upper end against the under side of the retaining plate 25 tends to hold the plunger P and the plate 25 in their upper or normal positions to retain the bolt L in its locking or latching position. When this spring is compressed by the depression of the plunger P, sufficient energy is stored 75 therein to restore the plunger and associated parts to normal position when the plunger is released.

The lock or latch may also be provided with means for automatically retracting the bolt L when the door is swung to closed position. We have herein illustrated a convenient arrangement in which the reciprocable operating member P is provided with a rigid arm 32 that projects outwardly at 85 right angles therefrom through the opening 12 in the front wall of the casing and carries an anti-friction roller member 33 at its outer end that is adapted to be engaged by the cam edge 34 that forms a part of the upper edge 90 of the recess 14 in the keeper plate K. The upper edge of the recess 14 is also shaped so as to provide a notch 35 at the rear end of the cam edge 34, which notch is adapted to receive the end of the arm 32 and the roller 95 33 into which these parts may be projected by the action of the spring 30 when the door is closed. This arrangement provides additional locking means on the lock and thereby assists in keeping it from rattling.

The operation of the parts will be obvious from the foregoing description and will now be briefly described. Starting with the parts in the position shown in Figure 1 in which the door is closed, a depression of 105 the operating member P by hand first releases the retaining plate or dog 25 by swinging it downwardly, and then the cam 20, acting upon the bolt L through the roller 19 and stem 18 causes spring 16 to bend and the bolt L to move rearwardly into the casing far enough to allow the door to be pushed open by the same hand that operates the plunger P. Of course, at the same time the roller 33 on the arm 32 has been 115 moved out of the notch 35 so that it will freely pass the lower end of the cam edge 34. In unlocking position the parts are substantially in the position indicated in Figure 2. After the door has been swung 120 free from the jamb the hand may be removed from the plunger P and the springs 16 and 30 will cooperate to restore the parts of the mechanism to the positions shown in Fig. 1.

In closing the door it is unnecessary to depress the plunger P by hand, the necessary retraction of the bolt L being automatically effected by means of the cam 34 on the strike plate K which cooperates with the 130

- roller 33 on the end of the arm 32 to depress the plunger upon which this arm is mounted. The arrangement is such that the plunger or operating member P will be 5 depressed a sufficient amount to move the bolt L inwardly so that it will not catch against the edge of the door jamb when the door is swung to close it. In order to assist in automatically moving the bolt L 10 inwardly, we may provide a depressed portion 151 on the keeper plate, such depressed portion extending from the outer edge of the keeper plate inwardly to the socket 15 and acting as a cam against the rounded 15 outer end of the bolt. At the moment the bolt L is in position to snap into the socket 15, the roller 33 is in position to snap into the notch 35 and the door will be closed and locked. The upper guide and brace plate 20 23 serves as a stop to limit the upward movement of the operating member P by engaging the arm 32 near where the latter is connected to the member P.

While we have shown and described the 25 invention in detail it is to be understood that certain features of construction may be modified without departing from the spirit of the invention and therefore our invention is not to be limited to the exact arrangement shown and described, which is 30 to be understood as merely illustrative of the broad principles involved.

What we claim is:

1. In a lock, or latch, the combination with 35 a casing, of swingably supported locking or latching means, and an operating member in said casing having cam means for cooperating with said means to move the same relatively to its locking or latching position.
2. In a lock or latch, the combination with 40 a swingably supported locking or latching element, of means movable with said locking element, means for operating the locking element comprising a reciprocable operating 45 member provided with cam means adapted and arranged to cooperate with the means movable with said locking element to move the latter from its locking position.
3. In a lock or latch, the combination with 50 a casing and a locking or latching element normally projecting therefrom, of means for locking or dogging said element in its projected position, cam means for moving said element from its projected position, and 55 means for operating said cam means and such locking or dogging means.
4. In a lock or latch, the combination with 60 a swingably supported locking or latching element, of means for operating the same comprising a reciprocable member having a rigid arm provided with a cam portion adapted and arranged to cooperate with 65 means on said element to move the latter from its locking or latching position.
5. In a lock or latch, the combination with 70 a bolt, of means for locking or dogging the same in its locking or latching position, and means for releasing said locking or dogging means and for operating said bolt comprising a reciprocable member having a rigid 75 arm provided with a cam surface adapted and arranged to cooperate with said bolt to move the latter from its locking or latching position.
6. In a lock or latch, the combination with 80 a bolt, of a leaf spring supporting the same in operative position, and cam means for cooperating with said bolt to move the latter from its operative position against the tension of said spring.
7. In a lock or latch, the combination with 85 a bolt, of means for moving said bolt from its locking or latching position comprising an operating member having an arm carrying a roller that is adapted and arranged for engagement by a keeper or strike plate.
8. In a lock or latch, the combination with 90 a bolt, of means for retaining said bolt in its locking or latching position comprising a pivoted member having a recess therein, and means for releasing such retaining means and bolt comprising a member projecting into said recess and provided with a pin arranged to cooperate with said pivoted member to swing it from retaining position relatively to said bolt.
9. In a lock or latch, the combination with 95 a swinging bolt carrying an antifriction roller, of cam means for engaging said roller and moving said bolt from its locking or latching position.
10. In a lock or latch, the combination with 100 a swinging bolt provided with spaced portions carrying antifriction means between them, of an operating member for said 105 bolt having cam means adapted and arranged to engage said antifriction means to operate said bolt.
11. In a lock or latch, the combination with 110 a swinging bolt carrying antifriction means, of a reciprocable operating member having cam means adapted and arranged to engage said antifriction means and move said bolt from its locking position, and means tending to restore said bolt to a locking or latching position.
12. In a lock or latch, the combination of 115 a casing, a bolt normally projecting therefrom and having an antifriction roller mounted on a part thereof inside the casing, 120 a leaf spring mounted in said casing and supporting said bolt in its projected position, a pivoted lever having one end adapted to retain said bolt in its projected or locked position, said lever having a recess therein, 125 a plunger or reciprocable operating member having a part projecting through said recess and a part accessible from the exterior of said casing, means on said plunger for engaging said lever to release said bolt, a cam 130

rigidly mounted on said plunger and movable therewith into engagement with said roller to retract said bolt into the casing, an arm mounted on said plunger and engageable by a keeper or strike plate to operate the plunger, and a spring for restoring the plunger when it has been depressed and for returning the bolt to its locking or latching position.

10 13. In a latch, the combination with a swingably supported bolt, of reciprocable cam means for moving said bolt, an operating handle connected to one side of said cam means, and resilient means cooperating with 15 and disposed on the other side of said cam means.

14. In a latch, the combination with a

swingably supported bolt, of reciprocable means for moving said bolt, comprising cam means, an operating handle connected to one 20 side of said cam means and extending upwardly therefrom, a stem connected to another side of said cam means and extending downwardly therefrom, and a helical spring surrounding said stem and cooperating with 25 such moving means to restore said cam means to normal position.

In testimony whereof we hereunto affix our signatures.

EDWIN CROMPTON.
CHARLES L. CROOKS.
